S. W. CLARK, OF PRAIRIE DU CHIEN, WISCONSIN, ASSIGNOR TO HIMSELF,
N. A. WRIGHT, AND W. A. TERRY, OF THE SAME PLACE.

Letters Patent No. 74,047, dated February 4, 1868.

IMPROVEMENT IN HAND-SPINNING WHEEL.

The Schedule referred to in these Letters Patent and making part of the same.

TO ALL WHOM IT MAY CONCERN:

Be it known that I, S. W. CLARK, of Prairie du Chien, in the county of Crawford, and State of Wisconsin, have invented a new and useful Improvement in Spinning-Wheel; and I do hereby declare that the following is a full, clear, and exact description thereof, which will enable others skilled in the art to make and use the same, reference being had to the accompanying drawings, forming part of this specification, in which the drawing is a side elevation of my improved self-drawing and winding spinning-wheel.

The nature of this invention consists in a novel and useful modification of the ordinary domestic spinning-wheel, enabling the operator to sit while spinning, and thus avoid the labor of walking to and from the head of the wheel, to spin the yarn or roving, and wind it on the cop, as usual. This object is accomplished by attaching the spindle to the end of a radial arm or sweep, which is pulled backward from the operator, to draw the roving to a position, where it remains, to twist the thread or yarn, by means of a weight and pulley acting steadily on the arm during the drawing movement, but directly under the control of the operator, and for winding the yarn into cop-form. The arm bearing the spindle is made to approach the operator, to receive another roll, by means of a treadle, as hereinafter more particularly described.

A represents an ordinary inclined frame, supporting the spinning-wheel B on the post C. On the forward end of the frame A are hung two pulleys on the same axis *a*. The small pulley *b* takes the driving-band *b'* from the spinning-wheel, and the large pulley *c* carries the band *c'* that turns the spindle *d*, placed on the upper end of the radial arm *D*, which is also fastened at its foot to the pulley-axis *a*. This axis *a* is hung in boxes, *e e*, fixed upon a sliding box, *g*, that is adjusted nearer to or further from the wheel *B*, as required, to tighten the pulley-band, by means of a set-screw, *h*, in a stationary block, *k*. A segmental groove, *m*, is formed in the lower end of the radial arm *D*, to which is fastened a cord, *m'*, that lies in the groove, and passes over a small pulley, *i*, set on a stud, *p*, on the side of the frame *A*, just forward of the spinning-wheel. The cord *m'* is connected at the other end to the treadle *q*, which is pivoted on the left side at the rear end of the frame. The upper end of a curved rod, *r*, with a weight, *r'*, attached to the lower end, is also fastened on the foot of the radial arm *D*. The weight *r'* is made adjustable on the rod *r* for the purpose of regulating the degree of tension on the yarn or roving, as hereinafter explained.

The operator, sitting with her toe on the treadle, draws the radial arm *D* toward her, by depressing the treadle, for the purpose of attaching the roll of wool or cotton or the roving to the spindle, and then releasing the treadle gently by raising the toe, and at the same time turning the wheel, as usual, with the right hand. The arm and spindle are drawn back from the operator by means of the weight *r'* on the curved rod *r*, which acts on the arm to pull it back with more or less force, according to the position of the weight and the leverage it exerts, in order to produce more or less tension on the yarn while it is drawn out, while, at the same time, the operator may regulate the receding and drawing movement by pressure on the treadle, which is connected with the arm *D* by the cord *m'*. When the arm *D* recedes to its limit, it remains in that position, at the will of the operator, long enough to twist the yarn, and is then brought forward again, by pressure on the treadle, to wind the yarn on the bobbin and receive another roll of wool or roving. Thus it will be seen that, by my improved spinning-wheel, the operation of spinning, by a person while sitting, may be performed perfectly, and that the drawing of the yarn by the adjustable weight is entirely under the control of the operator for producing a smooth, even thread.

I am aware that spinning-wheels have been previously made for spinning while the operator remains in a sitting position; but the difference between such wheels and my improvement is of an essential character in two marked particulars: first, instead of drawing the yarn out by the pressure of the foot on the treadle, this operation is accomplished, by my arrangement, with a weight, which gives a steady, regular movement to the radial arm, when it recedes, that cannot be imparted by the pressure of the foot alone; second, the yarn is elevated between the light and the operator, so that the bunches and inequalities can be easily detected, and thus the thread made smoother; and, third, the operator sits erect, looking upward, with the arms extended

and the chest expanded, instead of in a sloping position, looking downward at the work, as in other wheels of the kind, thereby promoting the health of the operator instead of injuring it.

Having thus described my invention, I claim as new, and desire to secure by Letters Patent—

The curved rod r , with the adjustable weight r' , attached to the radial arm D , the segmental groove m , cord m' , pulley i , and treadle g , in combination with the spinning-wheel C and the spindle d , placed on the upper end of the arm D , the whole being arranged and operated substantially as and for the purpose herein described.

S. W. CLARK.
